UNITED STATES PATENT OFFICE.

DAVID B. CARSE, OF SHARON, CONNECTICUT, ASSIGNOR TO SUPERIOR SIGN COMPANY, OF NEW YORK, N. Y., A CORPORATION OF DELAWARE.

REFLECTING-SIGN.

1,316,475.

Specification of Letters Patent. Patented Sept. 16, 1919.

Application filed May 11, 1918. Serial No. 233,860.

To all whom it may concern:

Be it known that I, DAVID B. CARSE, a citizen of the United States, residing at Sharon, in the county of Litchfield and 5 State of Connecticut, have invented certain new and useful Improvements in Reflecting-Signs, of which the following is a specification.

My invention consists of an improvement 10 in illuminated reflecting sign letters or characters, and has for its object to provide a series of outlining units adapted to partly or wholly form a sign letter, character or symbol, having means for providing continuous 15 reflecting surfaces, and series of co-acting reflecting facets, arranged at varying angles with relation to a source of light, in the manner more fully hereinafter set forth.

Illuminated signs have been heretofore 20 used composed of a series of individual reflecting facets extending from a plane base, but without any intervening angular surfaces, resulting in a lack of continuity of the design, and also utilizing individual sep- 25 arately attached reflectors.

In order to be practically efficient, it is also desirable that a reflecting sign may be easily visible from a wide range of varying view points at differing levels and angles.

30 By my invention I provide series of reflecting surfaces and faces which are practically visible from any point in front of the sign, irrespective of lateral position, within practicable limitations as to distance, because 35 of the supplementing effect of some of the reflecting faces on others of them, as herein-after described.

My invention utilizes the entire area of 40 the letter or character, greatly increasing the reflection, and producing continuous outlines forming complete unitary or composite characters.

In the drawings,

Figure 1 is a face view of the letter E 45 made in accordance with my invention;

Figs. 2 and 3 are vertical sections on the lines II, II and III, III of Fig. 1;

Fig. 4 is a cross section on the line IV, IV of Fig. 1;

50 Fig. 5 is a detail view of a unitary element adapted to form part of a curved letter or figure;

Fig. 6 is a cross section on the line VI, VI of Fig. 5;

55 Fig. 7 is a detail sectional view showing a

composite reflecting element permitting for adjustability of one member on the other.

In making an entire letter, figure or other symbol, I utilize one or more unitary base elements A adapted to be secured to a supporting foundation base 2 by screws 3 at suitable locations. 60

Each base A is provided with an inclined reflecting face 4 of say 20° and a series of projecting individual reflectors extending 65 therebeyond having reflecting facets 5 of a greater inclination, say at 45°, to the plane of the base 2.

The reflecting faces 4 and facets 5 are so arranged as to confront generally in the 70 direction of a source of light, as a lamp 6, the top of which is obscured as by frosting 7 or by suitable coloring, or otherwise.

Lamp 6 extends from a socket 8 in base 75 2 and the lamp or lamps are arranged centrally, as nearly as possible, of the general series of reflecting surfaces, for the best results. The several units A are each integral, preferably of pressed glass or metal, in hollow formation, so that the inner sides of the 80 reflecting portions may be suitably silvered as at 6, if of glass, for the best results as to reflecting efficiency.

If desired, the faces 4 and 5 may be disposed at double opposite angle slopings, as 85 in the case of the middle unitary base in the letter E, or any other cases in which a base is located between two lamps.

The angles of the several continuous faces 4 and of the individual facets 5 are variously 90 arranged for the best reflection, with relation to the lamp or lamps. By reason of the continuity of the comparatively flat or more nearly level faces 4 they form a reflecting background for the more highly reflecting 95 steeper projecting facets 5. There is thereby provided a continuous unbroken letter or symbol of reflected light, accentuated by regularly spaced synchronous facets of greater brilliance. If desired, the face or 100 faces 4 or 5 may be broken up by the use of any suitable means, as individual facets or reflectors, as Fresnell lenses.

By my invention, I provide a series of standard units which may be used in making 105 up any letter of the alphabet, or figure, or other symbol, providing complete continuous reflecting outlines and utilizing the greatest possible lamp power.

In Fig. 7 I show a modified construction 110

in which the projecting reflector having the steep facet 5^a is provided with an opening in the face 4^a of base A'. By this construction I am enabled to turn the individual reflector to locate its facet at varying angles with relation to the lamp, or to raise or lower it on its supporting base.

The invention may be otherwise changed or varied in different features or details, number of elements, angularity of the faces, etc., by the designer, but all such changes are to be considered as within the scope of the following claims.

What I claim is:

15. 1. A reflecting sign member adapted to be mounted on a plane supporting surface and to be combined with other similar members consisting of a base having a rear plane attaching face and a reflecting front portion relatively inclined thereto.
20. 2. A reflecting sign consisting of a symbol-outlining portion having a rear attaching base, a reflecting front portion relatively inclined thereto, and a series of supplemental reflectors extending beyond said front portion.
25. 3. In combination with a supporting base having a lamp extending therefrom, a symbol-defining element having an inclined face confronting the lamp and a series of integral projecting reflectors having reflecting facets of a steeper angle.
30. 4. A unitary element adapted to form the whole or part of a symbol of the class described consisting of a hollow pressed piece of glass having a projecting outlining body portion with an inclined surface, and a series of integral reflecting projections extending beyond the surface thereof and having reflecting faces of steeper inclination.
35. 5. A unitary element adapted to form the whole or part of a symbol of the class described consisting of a hollow pressed piece of glass having a projecting outlining body portion with an inclined surface, and a series of integral reflecting projections extend-

ing beyond the surface thereof and having reflecting faces of steeper inclination and provided with an interior coating of suitable reflecting material.

50

6. A unitary element adapted to form the whole or part of a symbol of the class described consisting of a hollow pressed piece of suitable material having a rear attaching base and a projecting outlining body portion provided with a reflecting front relatively inclined to the plane of said base, and a series of separately attached reflectors extending beyond said reflecting front and having socketed engagement with said element.

55

7. In combination with a supporting base provided with one or more lamps projecting therefrom, a sign character composed of a series of suitably arranged main reflecting members attached to the base extending outwardly therefrom having main reflecting faces disposed toward the lamp or lamps and provided with individual projecting reflectors having similarly disposed faces of steeper inclination.

60

8. In a sign, a plurality of letter elements adapted to be assembled for forming a desired letter and having rear base portions and front reflecting portions.

65

9. In a sign, a plurality of letter elements adapted to be assembled for forming a desired letter and having rear base portions and front reflecting portions, and one or more reflectors adjustably mounted thereon and each having a reflecting surface inclined thereto.

70

10. In combination with a rear supporting structure having a plane attaching surface, a reflecting sign member consisting of a base having a rear plane attaching face in holding contact with said attaching surface and provided with a reflecting front portion relatively inclined to said rear plane face.

75

In testimony whereof I hereunto affix my signature.

DAVID B. CARSE.
